UNITED STATES PATENT OFFICE.

JAMES KEITH AND GEORGE KEITH, OF LONDON, ENGLAND.

DEVICE FOR LIGHTING AND EXTINGUISHING GAS-LAMPS.

1,103,517.

Specification of Letters Patent. Patented July 14, 1914.

Application filed February 16, 1914. Serial No. 818,955.

To all whom it may concern:

Be it known that we, JAMES KEITH and GEORGE KEITH, subjects of the King of the United Kingdom of Great Britain and Ireland, and residents of London, England, have invented a certain new and useful Improvement in Devices for Lighting and Extinguishing Gas-Lamps, of which the following is a specification.

10 This invention relates to means for use in lighting and extinguishing the burners of high pressure gas lamps by variation of the pressure of the gas supply.

15 The invention contemplates the provision of devices whereby it is rendered possible to extinguish certain burners of an installation without affecting other burners on the same main.

20 In accordance with the invention, the gas supply valve is adapted to be automatically opened when the ordinary gas pressure *i. e.*, that prevailing in the main is increased to high working pressure and to be automatically closed when the pressure is temporarily 25 further increased in excess of the working pressure, the supply valve remaining closed on restoration of the high pressure and during the subsequent period of ordinary pressure. Further, the supply of gas to the pilot 30 light tube is automatically controlled in such manner that such supply is restricted during periods of high pressure.

35 To control the supply of gas there is provided a diaphragm interposed between the body of the supply valve and a chamber communicating with the pilot light, said diaphragm constituting the closing element of the supply valve and being normally held against the valve seat by a plunger loaded 40 preferably by a spring. The inlet end of a the supply valve is connected by means of a controllable by-pass conduit with said chamber while communication between said chamber and the pilot tube is established by an 45 orifice controlled by a valve float and a constricted by-pass.

50 The load acting on the plunger is so adjusted that the ordinary gas pressure is insufficient to disengage the diaphragm from the seat of the supply valve, but when the ordinary pressure is increased to high working pressure the diaphragm will be forced back to permit the flow of gas to the burner or burners.

55 On sudden increase of the high working pressure above a definite limit, the valve float

is raised by the action of a loaded piston to close the orifice communicating with the pilot tube. Owing to the outflow of gas from the chamber to the pilot tube being thus checked 60 by the valve float, the pressure in the chamber becomes equal to that acting on the diaphragm on the side adjacent to the supply valve. Consequently, the diaphragm is forced upon the seat of the supply valve by the said 65 loaded plunger and maintained in this position after the expiration of the temporary increase of pressure, the pilot tube receiving a continued supply of gas at high pressure through the constricted by-pass. These 70 conditions prevail until the high working pressure is reduced to the ordinary pressure, whereupon normal conditions are reestablished.

75 It will be understood that certain of the lamps may be equipped merely with a lighting device comprising a supply valve controlled by a diaphragm interposed between said supply valve and a chamber connected directly to the pilot tube, the valve float and 80 the loaded piston constituting the main elements of the extinguishing device proper being in this case omitted. The burners so equipped are automatically extinguished when the high working pressure is reduced 85 to ordinary pressure and are not affected by a temporary increase of the pressure of the gas above the high working pressure in order to extinguish burners provided also with the extinguishing device. Further it 90 will be understood that individual burners or groups of burners provided with the extinguishing device may be extinguished at different times according to the adjustment 95 of the load on the piston of the extinguishing devices of the respective burners.

The invention is illustrated in the accompanying drawings in which—

Figure 1 is a vertical section and Fig. 2 a horizontal section of the improved lighting and extinguishing device. Fig. 3 is an elevation and Fig. 4 is a part plan part horizontal section of automatic extinguishing means detachably secured to the lighting device proper.

105 The same reference characters denote similar parts in the several views.

Referring to the drawing, 1 denotes the casing of the automatic gas supply valve. To said casing 1 is connected a casing 1^a 110 which contains the means hereinafter described, for extinguishing the flame at the

main burner and for controlling the flow of gas to the pilot light. The casing or valve body 1 is sub-divided by a web 2 to form an inlet compartment 3 communicating by way of an orifice 4 with an annular recess 5 formed in the side of the casing 1 adjacent to the casing 1^a, and an outlet compartment 6 communicating with an orifice 7 located centrally of said annular recess 5. Interposed between the casing 1 and the adjacent cup-shaped chamber 1^b in the casing 1^a is a diaphragm 8 which covers the annular recess 5, and is adapted to engage the seat 9 presented by the circular ridge 15 which surrounds the orifice 7, the said diaphragm being pressed toward said seat by the head 10 of a plunger 11 slidably arranged within a cylindrical recess 12 and acted on by a spring 18. As will be evident, the engagement of said seat by said diaphragm prevents admission of gas to the burner while ordinary pressure prevails in the main; when, however, the pressure is increased to high working pressure, the diaphragm is forced away from the seat and gas is allowed to flow by way of the outlet compartment 6 to the burner or burners.

A port 19 permanently in communication with the annular recess 5 communicates by way of two orifices 20^a and 21^a with the cylindrical recess 12 (see Fig. 2); the flow of gas into the recess 12 through either of said orifices being controlled by means of regulating screws 20 and 21 respectively, the orifice 20^a being adapted also to be entirely closed by means of a valve member 13 formed on the end of the plunger 11 when said plunger is forced into the recess 12 by high pressure of gas acting on the diaphragm. The gas admitted to the cylindrical recess 12 passes through a channel 14 in the plunger 11 into the chamber 1^b, whence it flows to the pilot tube 16 by way of the port 15, a cylindrical chamber 8^a and a recess 13^b in a valve float 13^a movable within an extension 12^a of the chamber 8^a.

Movable within the chamber 8^a is a piston 7^a formed with a valve element 2^a adapted to rest on a seat 3^a presented by the edge of a cylindrical recess 3^b of the casing 1^a, said recess 3^b communicating with the port 19. The piston 7^a and valve element 2 are loaded preferably by a tension spring 4^a equipped with adjusting means including a rotatable screw 5^a projecting beyond the lower end of said casing 1^a and passing through a gland 6^a connected thereto.

The port 15 is so disposed that when the piston 7^a is in its normal position, as shown, the said port 15 is exposed so as to communicate with the space in the chamber 8^a above the piston 7^a. The valve float 13^a located within the extension 12^a of the chamber 8^a normally rests at its lower end

on the upper face of the piston 7^a, the upper conical end 14^a of the valve float or float valve 13^a being adapted to engage a seat 15^a formed at the top of the extension 12^a, said extension 12^a communicating directly with the pilot tube 16, an auxiliary means of communication between said extension and the pilot tube 16 being afforded by a by-pass connection 22 adapted to be controlled by a regulating screw 23.

The spring 4^a is so adjusted that when the pressure of gas is increased to exceed the high working pressure, the said valve element 2^a is raised from its seat, the escaping gas acting upon the increased area afforded by the lower face of the piston 7^a, thus causing the latter to be blown suddenly upward within its chamber 8^a, the initial movement of the piston 7^a first causing the port 15 to be closed, and further upward movement of the piston permitting communication between the port 15 and the space on the lower side of the piston 7^a. Simultaneously the movement of the piston 7^a causes the upper end 14^a of the valve 13^a to engage its seat 15^a, thus obstructing the direct outlet to the pilot tube 16. The high pressure gas acting beneath the piston passes by way of the port 15 to the chamber 1^b so as to counterbalance the pressure of gas tending to maintain the diaphragm 8 out of engagement with the seat 9, whereby the spring 18 acting on the head 10 of the plunger 11 is enabled to force the diaphragm 8 on to its seat 9, thus shutting off the supply of gas to the burner or burners. Thereupon the gas leaks past the piston 7^a to the upper face thereof and eventually its pressure counterbalances the pressure acting on the lower face of the piston 7^a, thereby permitting the valve element 2^a to be closed by the action of the spring 4^a. The pressure of gas now inclosed in the chamber 8^a above the piston 7^a is sufficient to maintain the upper end 14^a of the valve 13^a in engagement with the seat 15^a so that the pilot tube receives its supply of gas through the by-pass 22. Owing to the outlet from the extension 12^a to the pilot tube being thus partially obstructed, the pressure in the chambers 8^a and 1^a is not reduced below the high working pressure on expiration of the period of excess pressure, the weight of the valve 13^a being such that it will be maintained in engagement with the seat 15^a by the high working pressure. High working pressure is maintained in the chambers 1^b and 8^a by the ingress of gas to the chamber 1^b by way of the orifices 20^a and 21^a; consequently the diaphragm 8 remains in engagement with the seat 9 until the pressure of gas is reduced to the ordinary pressure, whereupon the valve 13^a drops, leaving the diaphragm 8 free to act when the next lighting-up time arrives.

The construction shown in Figs. 3 and 4

is substantially the same as that described with reference to Figs. 1 and 2, save that the casing 1^a of the extinguisher is detachably connected to the chamber 1^b containing the diaphragm 8, a pipe connection 28 being attached to said chamber and leading to a branch opening into the chamber 8^a within which the piston 7^a operates, the pipe connection 28 being substituted for the port 15. 5 In this case, the regulating screw 21 is removed and its corresponding orifice plugged as indicated at 29, Fig. 5, the regulating screw 30 serving in lieu thereof passing through an orifice 31 permitting a free supply of gas to pass to the recess 3^b of the casing 1^a by way of the port 19. 10

We claim:—

1. Means for automatically lighting and extinguishing gas lights, said means comprising a valve body through which the supply of gas passes, said valve body provided with a seat, a diaphragm adapted to engage said seat and to cut off passage of gas through said valve body, means tending 20 to press said diaphragm against said seat, a chamber at the side of said diaphragm remote from said seat, said chamber formed with a by-pass conduit connecting the inlet end of said valve body with said chamber, 25 a pilot tube communicating with said chamber, a second chamber communicating with said pilot tube, a loaded piston movable in said second mentioned chamber, the part of said second mentioned chamber beneath said 30 piston being in communication with the inlet end of said supply valve body, and a valve float adapted to be actuated by said piston to obstruct communication between said first mentioned chamber and said pilot 35 tube. 40

2. Means for automatically lighting and extinguishing gas lights, said means comprising a valve body through which the supply of gas passes, said valve body provided 45 with a seat, a diaphragm adapted to engage said seat and to cut off passage of gas through said valve body, means tending to press said diaphragm against said seat, a chamber at the side of said diaphragm remote 50 from said seat, said chamber formed with a by-pass conduit connecting the inlet end of said valve body with said chamber, a pilot tube communicating with said chamber, a second chamber communicating with 55 said pilot tube, a loaded piston movable in said second mentioned chamber, a valve element connected with said piston, the part of said second mentioned chamber beneath

said valve element being in communication with the inlet end of said supply valve body, 60 and a valve float adapted to be actuated by said piston to obstruct communication between said first mentioned chamber and said pilot tube. 65

3. Means for automatically lighting and extinguishing gas lights, said means comprising a valve body through which the supply of gas passes, said valve body provided with a seat, a diaphragm adapted to engage 70 said seat and to cut off passage of gas through said valve body, means tending to press said diaphragm against said seat, a chamber at the side of said diaphragm remote from said seat, said chamber formed with a by-pass conduit connecting the inlet 75 end of said valve body with said chamber, a valve member adapted to obstruct communication between said conduit and said chamber, a pilot tube communicating with said chamber, a second chamber communicating with said pilot tube, a loaded piston movable in said second mentioned chamber, a valve element connected with said piston, the part of said second mentioned chamber beneath said valve element being in communication 80 with the inlet end of said supply valve body, and a valve float adapted to be actuated by said piston to obstruct communication between said first mentioned chamber and said pilot tube. 85

4. Means for automatically extinguishing gas lights, said means comprising a pilot tube, a casing having a chamber communicating with said pilot tube, said casing being provided with upper and lower valve 95 seats and with a port of admission of gas to said chamber, a loaded piston movable in said chamber and adapted to cover and uncover said port, a valve element connected with and below said piston and adapted to engage said lower valve seat, the part of said chamber beneath said seat having an opening for admission of gas under pressure in excess of the working pressure, and a valve float or float-valve adapted to be lifted 100 by said piston against said upper valve seat to obstruct passage of gas to said pilot tube. 105

In testimony whereof we have signed our names to this specification in the presence of two subscribing witnesses.
